RECORD MAKING MACHINE

William H. van Hacht, Bronxville, N. Y., assignor
to Underwood Elliott Fisher Company, New
York, N. Y., a corporation of Delaware

Application May 6, 1938, Serial No. 206,435

27 Claims. (Cl. 197—66)

This invention relates to typewriters and other record making machines and more particularly to a power operated carriage return mechanism and to certain associated mechanisms for such machines.

One object of the invention is to improve the construction and mode of operation of power operated carriage return mechanisms for record making machines and provide a novel and improved mechanism by which the carriage of such a machine may be returned by power either to partially returned or to fully returned position.

Another object of the invention is to provide record making machines having carriage return mechanism operated by power with novel and improved means for stopping the movement of the carriage with the carriage in either of two different positions.

A still further object of the invention is to provide record making machines, having a carriage and power means for imparting return movements to the carriage, with novel and improved means for disconnecting the power means from the carriage and stopping the return movement of the carriage.

The invention is illustrated in this application as applied to a machine of the Elliott-Fisher type having a paper support which is fixed in the direction of letter space movement of the carriage and a type or key carriage movable across the machine in a right hand direction to letter space and a still further object of the invention is to provide, for machines of this type having power operated mechanism for moving the carriage in a left hand direction to return the same, mechanism for stopping the return movement of the carriage in either partially returned or fully returned positions.

With the above and other objects in view the invention consists in the novel and improved features hereinafter described and particularly pointed out in the claims, the advantages of which will be readily understood and appreciated by those skilled in the art.

The invention will be clearly understood from the accompanying drawings illustrating the invention in its preferred form and the following detailed description of the constructions therein shown.

In the drawings:

Figure 1 is a front view of the well-known Elliott Fisher flat-bed typewriting machine, partly broken away at a central point, and also at either end, to which the present invention is applied, the parts being shown in their normal

positions to arrest the carriage upon return to the left-hand margin;

Figure 2 is a fragmentary plan view of one means to control the disengagement of the clutch members between the motor and the carriage, said means being shown in its normal idle position;

Figure 3 is a front view, broken away to enable a more complete showing of the invention, the parts being in their actuated positions assumed when the carriage is arrested after a partial return only;

Figure 4 is a fragmentary top plan view complementing Figure 2, and showing the clutch disengaging control in operated position;

Figure 5 is an end view of an Elliott Fisher carriage, showing the special partial carriage return key and connected parts in their normal positions;

Figure 6 is an enlarged detail view of the means for releasing the latched section of the partial carriage return mechanism, for return to normal;

Figure 7 is a perspective detail view, showing a modification, wherein the line space mechanism is utilized to effect disconnection of the clutch members between the motor and the carriage;

Figure 8 is a fragmentary detail rear view of a part of the line spacing mechanism, partly broken away; and

Figure 9 is a detail plan view illustrating certain of the parts shown in Figure 7.

As the present invention utilizes much of the mechanism shown in U. S. Patent 1,904,127, reference thereto may be had for a more complete understanding of such features as will be briefly referred to herein.

The Elliott Fisher machine includes a line space frame formed of front and rear rails 11 connected by stretcher bars 10, and supported on tracks 12, forming the side bars of the platen frame, to enable the line space frame to shift towards and from the operator in line spacing direction and return.

A key or type carriage 13 is provided with wheels 14, traversing the transversely extending front and rear rails 11 of the line space frame, to enable a carriage travel in letter spacing direction and return.

Escapement mechanism (not shown) of any suitable nature, including the customary spring drum, forces the carriage in letter-spacing direction under control of the usual keys 15 mounted in the key carriage, as shown in U. S.

patent to Foothorap, No. 1,203,519, October 31, 1916, for instance, in conjunction with Patent No. 1,904,127, above referred to.

The power carriage return mechanism includes a motor 16 (Fig. 5), connected by a worm 17 and worm gear 18 to a countershaft 19 suitably journaled in brackets (not shown) extending rearwardly from the rear rail 11 of the line space frame, as illustrated in Patent No. 1,904,127.

Coacting clutch members 20 and 21, the member 20 being fast on the countershaft 19, and the member 21 being loose on the shaft for axial movement relatively thereto, are interposed between the motor and the carriage 13.

A wide carriage return gear 22 fast on the forward end of the grooved sleeve or collar 23 of the loose clutch member 21, maintains engagement with a carriage return rack 24 in any position of the loose clutch member 21, the rack being mounted on an apron 25, projecting from and extending across the rear end of the key carriage 13.

The clutch members 20, 21 are normally held disengaged by a rearwardly extending latch 26 pivoted on a cross shaft 27, the hooked rear end of which latch takes over the laterally turned upper end of an arm 28 fast on a suitably journaled clutch shifting shaft 29. A clutch shifting finger 30, fast on the shaft 29, extends its upper rear end into the peripheral groove in the sleeve or collar 23. A spring link 31 connected to studs 32 and 33 on the latch 26 and on the clutch shifting arm 28, respectively, retains the latch effective, to hold the clutch shifting finger 30 at the clockwise limit of its travel, and the loose clutch member 21 disengaged from the fast clutch member 20.

A rearwardly extending fan-tailed or wedge shaped arm 34, one end of which is fast on the cross shaft 27, enters between the spring anchoring studs 32 and 33, to control the latch 26 and clutch members 20 and 21, the wedge shaped arm being rocked by a bail 35, comprising a horizontally extending tooth bar connected by arms to the cross shaft 27.

Complementary trip cams 36 and 37 (Figs. 7, 1 and 4) are adjustably located on the bail 35 to be contacted by tappets 38 and 39 (Figs. 1 and 3), spaced apart and offset relatively to each other, such tappets being mounted on the travelling key carriage 13. The trip cam 36 is adjustable along the bail 35 to the desired location at which the coaction of the right hand tappet 38 with the cam will occur immediately adjacent the predetermined end of a line of writing, and the trip means 37 is adjustably located at a point approximately corresponding to or slightly in advance of the starting point of the line of writing, to be wiped by the left hand tappet 39 as the carriage, on its return travel, approaches the beginning of a line.

The carriage 13, as it approaches its limit of travel in letter spacing direction, wipes the right hand tappet 38 past the right hand cam 36, thereby rocking the bail 35, shaft 27 and clutch controlling arm 34 in clockwise direction, Fig. 5. The arm 34, during this movement through its engagement with the stud 32 on the latch 26, disengages the latch from the clutch shifting arm 28, and additionally tensions the spring link 31, which thereupon rocks the clutch shifting arm 28, shaft 29 and clutch shifting finger 30 to slide the loose clutch member 21 into engagement with the clutch member 20 fast on the motor driven countershaft 19.

For present purposes, the motor 16 may be considered as continuously running, although that shown in Foothorap 1,904,127 is an intermittently running motor, which necessitates the provision of means shown in that patent, for completing and interrupting a motor circuit, not herein shown, though it could be used in place of the continuously running motor.

Immediately upon the engagement of the clutch members 20 and 21, power from the motor rotates the pinion 22 to return the carriage towards the beginning of a line, and as the carriage on such return, approaches the predetermined left hand limit of its travel, the left hand tappet 39, (Fig. 3), wipes past the oppositely faced left hand cam 37 (Fig. 4) complementary to the cam 36 (Fig. 7), near the opposite end of the bail 35, which cam 37 has been interposed in the path of the tappet 39 by the forward or clockwise rocking of the bail under the influence of the right hand tappet 38 and cam 36. The wiping contact of the tappet 39 with the cam 37 returns the bail 35 and the arm 34 counter-clockwise, (Fig. 5), to their normal positions.

The arm 34, upon such return, through its engagement with the stud 33 on the clutch control arm 28, rocks the latter and the clutch finger 30 in a clockwise direction (Fig. 5) to disengage the driven clutch member 21 from the driving clutch member 20. The movement of the arm 28 carries the laterally turned lip on said arm forwardly beyond the shoulder of the latch, and the latter then snaps down under the action of spring 31 to retain the clutch members disengaged.

The normal left hand margin stop 40 (Figs. 1, 3 and 5), mounted on the left hand end of the customary letter spacing rack 41 parallel with and rigidly connected to the rear rail 11, arrests the carriage at the extreme limit of its return travel.

As in the Foothorap Patent 1,904,127, line spacing mechanism adapted for both manual and automatic operation, is provided, and recourse to such patent may be had for a more complete description thereof, the present invention being more particularly directed to the means for effecting return of the carriage 13 from an advanced position in letter spacing direction to a precedent position short of a complete return to the left hand marginal position and utilization of the control of the line spacing mechanism for automatic operation upon such partial return of the carriage.

Line spacing mechanism

The line spacing mechanism is based on that shown in Foothorap Patent 1,275,413, August 13, 1918, modified as shown in Foothorap Patents 1,914,885, June 20, 1933, and 1,930,433, October 10, 1933, and is constructed substantially as shown in Patent 1,904,127.

A shaft 42 (Figs. 7 and 8), journaled at its opposite ends in vertical brackets 43 (Figs. 1 and 7), projecting upwardly from the rear corners of the line space frame 10, 11, carries toothed line spacing gears 44 fast thereon and in mesh with racks 45 mounted on the side rails 12 of the platen frame.

At its right hand end (Fig. 7), the line spacing shaft 42 projects through its supporting bracket 43 and has a finely toothed line space ratchet 46 secured thereto. A line space pawl carrier or arm 47, journaled on the line space shaft, supports at its radially projecting outer end a line

space pawl 48 pivoted at 49, to overhang the toothed periphery of the ratchet 46. A stud 50 on the pawl carrier 47 projects into an elongated recess 51 at the inner end of the pawl to limit its rocking travel in opposite directions.

A spring (not shown, but see Figs. 33 and 35 of Patent No. 1,904,127), attached to the pawl carrier 47 at a point on the opposite side of the line space shaft 42, normally returns the pawl and pawl carrier to and yieldingly holds them in their normal positions at one end of their travel, as shown in Fig. 7. In such position, the inner end of the pawl 48 contacts an adjustable line space stop 52, to maintain the pawl disengaged from its ratchet. Adjustment of the stop enables the line spacing interval to be varied.

A driving bell crank 53 is journaled on the line space shaft 42 adjacent the pawl carrier 47, one arm of which driving lever carries a stud 54 entered in a slot 55 in the outer end of the line spacing pawl 48. The remaining arm of the bell crank 53 (see Fig. 8), projects rearwardly from the line space shaft 42, the outer end of such rearwardly extending arm being connected by a link 56 to one end of an intermediate lever 57 pivoted between its ends at 58 to the adjacent vertical bracket 43. A second link 59 connects the remaining end of the intermediate lever 57 to the outer end of an arm 60 projecting radially from the rear end of a stub shaft 61 (Figs. 1, 3 and 7), journaled in lugs 62 (Fig. 7), depending from a lateral bracket 63 projecting outwardly from the vertical bracket 43.

One arm of an elbow lever 64 fast on the front end of the stub shaft 61, is hooked to form a terminal for one end of a spring link 65, the opposite end of which spring link engages a hook on the lower arm of a lever 66 loosely mounted on the stub shaft 61. An offset lip 67 on the opposite arm of the elbow lever 64 lies in the path of a shoulder 68 on the lever 66, the spring link normally maintaining the lip 67 and shoulder 68 in contact.

A draw rod 69 adjustably secured at its right hand end to the upper arm of the loose lever 66 on the forward end of the stub shaft 61, extends transversely of the line space frame and is confined in a channel formed between the front face of the rear rail 11 and the rear face of the letter spacing rack 41. The left hand end of the draw rod 69 (Figs. 1, 3 and 5), passes through a guiding eye 70 secured to a bracket 71 projecting horizontally from the left hand vertical bracket 43. A cap nut 72 threaded on the left hand end of the draw rod 69 facilitates assembly, and prevents disengagement of the draw rod and eye, when the draw bar is slid in one direction.

Should operation of the line space ratchet be prevented for any reason, the spring link 65 will yield to relieve the line spacing mechanism of strain, and prevent breakage.

A catch 73 (Figs. 1, 3 and 5), is adjustably locked at any of several positions along the left hand end of the draw rod 69, to coincide, approximately, with the position to which the left hand margin stop 40 is set along its rack 41.

A coacting catch 74 pivoted at 75 to a hanger 76 projecting from the left hand side of the carriage 13, is normally held in position to engage the catch 73, by a spring 77, one end of which is attached to the tail of the catch 74 to hold the catch at one limit of its rocking movement determined by a stop pin 77a.

The depending hook shaped catch 74 is lo-

cated in advance of the adjustable carriage stop 78 (Figs. 1 and 3) which coacts with the left hand margin stop 40, when the key carriage is being returned to the beginning of a line, so that as the key carriage approaches its left hand margin, the depending catch 74 will first engage its coacting catch 73 near the left hand end of the draw rod 69 and pull the latter catch together with the draw rod 69 to the left. The draw rod, through its connection with the loose lever 66, rocks the latter and through the spring link 65 rocks the stub shaft 61 in the same direction to actuate the connections 60, 59, 57 and 56. Through these connections the bell crank 53 is advanced in counter-clockwise direction (Fig. 7) first rocking the line space pawl 48 on its pivot 49 to effect its engagement with the toothed periphery of the line spacing ratchet 46, after which continued advance of the bell crank 53 turns the ratchet, the shaft 42 and gear wheels 44 to advance the key carriage.

As the bell crank approaches the limit of its advance rotation, the line space pawl advancing therewith, collides with an abutment 79, which arrests farther advance of the pawl and its train of mechanism back through lever 64, the pawl, by reason of such contact, being forced more firmly into engagement with the ratchet 46 to lock the ratchet against continued rotation, thus preventing overthrow of the carriage in line spacing direction.

Substantially simultaneously with the arrest of the line spacing operation, the adjustable carriage stop 78, (Figs. 1 and 3), contacts the left hand margin stop 40 to arrest the carriage, at which time a lateral stud 80 extending forwardly on the depending catch 74 has escaped past and is caught behind a by-pass cam 81 on the margin stop 40 as shown in Patent 1,904,127. The carriage escapement mechanism holds the carriage at the end of its extreme left hand travel, as limited by the margin stop with the line space mechanism locked in overthrow preventing position until, upon the depression of any letter spacing key, the carriage shifts one step to the right, causing the stud 80 to ride up the cam 81 to disengage the coacting catches 73 and 74.

Thereupon the usual springs (see Patent No. 1,719,176, dated July 2, 1929, Foothorap) acting respectively on the pawl carrier 47 and the bell crank 53 operate to swing these parts rearwardly of the machine thereby restoring the pull rod 69 and the catch 73 to their normal positions. During this movement of the parts, the pawl 48 is rocked to disengage it from the ratchet 46 and the pawl carrier and pawl swing rearwardly with the lever 53 until the pawl is arrested by contact with the adjustable abutment 52.

To enable the operator to effect a motor driven carriage return from any point intermediate between the beginning and end of a line, it is customary to provide a special "Carriage return" key, depression of which operates a finger to rock the carriage return clutch bail 35 and effect an engagement of the clutch members 20, 21 (Fig. 5), to connect the motor with the carriage return pinion 22.

The clutch members are disengaged upon the arrival of the carriage at the beginning of a line, by the wiping contact of the tappet roll 39 (Fig. 3), with the cam 31, as heretofore explained.

The foregoing is, in the main, old, and constitutes a part of the present invention only

insofar as it cooperates with the novel features now to be set forth.

Partial carriage return

It may often be desirable, in accounting operations, in paragraphing, or for other reasons, to effect a return movement of the carriage of a typewriting machine in contra-letter spacing direction from any advanced position to a precedent position short of a complete return to the beginning of a line.

To this end, I have contrived a means under control of the operator which not only effects connection of the power with the carriage, at any desired point in the letter spacing travel of the carriage beyond the place at which the carriage will be arrested short of a complete return, but also simultaneously disables the normally effective line space initiating device, and substitutes another therefor.

Furthermore, such operator controlled means shifts an arrester from idle to effective position, and may position a normally ineffective clutch disabling control for operation.

Referring to Figure 5 of the drawings, I utilize the special key 100 heretofore provided to initiate the return movement of the carriage from any point short of the end of a line, as a partial carriage return key, it being obvious that the former carriage return key could be retained, and a second key arranged to contact my improved partial carriage return mechanism.

In either event the key lever 101 of the special key 100 is pivoted at 102 (Fig. 5) to the rear of the key carriage 13, a bell crank 103 being pivoted co-axially with the key lever, and having an ear on one arm connected by a spring link 104 with a similar ear on the tail of the key lever.

Should the bell crank be blocked from operation, the spring link 104 will yield to avoid straining the bell crank 103 and its connected parts.

A depending arm of the bell crank 103 is slotted to embrace a wrist 105 on an arm 106 fast on, and projecting radially from a shaft 107 extending part way across the carriage and journaled in flanges 108 projecting upwardly from the apron 25 supporting the carriage return rack 24.

The inner or right hand end of the shaft 107 carries a finger 109 depending to a point behind the universal clutch bail 35, the finger travelling with the carriage and being operable upon depression of the key 100, to rock the clutch bail 35 forwardly, in any position assumed by the key carriage in its letter spacing travel, against the tension of a return spring 110 (indicated by dotted lines) coiled about the shaft.

A stud 111 projects laterally from the horizontal key lever 101, and passes through a slot 112 in the horizontal arm of the bell crank lever 103 parallel with the key lever, the spring 104 maintaining the key in its normally elevated position, determined by contact of a face on the key lever with the underside of a slotted plate 113 through which the stem of the key passes.

In normal position, the stud 111 occupies the upper end of the slot 112 in the horizontal arm of the bell crank lever, as shown in Figure 5.

The spring link 104 has the additional function of permitting the bell crank 103, arm 106 and bail operating finger 109 to rock to their normal positions when the carriage 13, on its return, wipes its disengaging tappet 39 past the left hand cam 37,

even though the key 100 is accidentally or purposely held depressed, thus to enable the automatic disconnection of the motor from the carriage when the latter has been arrested in its left hand marginal position.

Nor can the finger 109 become effective to engage the clutch members 20, 21, until the carriage has advanced in letter spacing direction a sufficient distance to withdraw the disengaging tappet 39 from the cam 37.

One means to enable the operator to simultaneously shift the normally effective line spacing catch 74 (Figs. 1 and 3), to idle position and substitute an earlier operating catch therefor, and also to introduce an earlier acting carriage arresting member, controlled from the special carriage return key 100 which throws in the clutch connection between the motor and the carriage, whereby the operator, by depression of 20 a single key, may effect all three results, is as follows:

A thrust bar 114 (Fig. 5), the upper end of which is pivotally attached at 115 to the horizontal arm of the bell crank 103, depends therefrom, its lower end passing loosely through an eye 116 for guidance and having a collar 117 adjustably secured thereto to contact the eye. The eye 116 is clamped to the lever 118 in a position between the ends of said lever, the front end of 30 which lever is pivoted at 119, to a hanger 120 depending from a bracket 121 secured to the left hand side of the travelling carriage 13. The rearward free end of the lever 118 overhangs a leftward extension 122, (Figs. 1 and 3), of the travelling catch 74. The left hand end of the extension 122 is shouldered, as at 123, to coact with the catch 73 adjustable along the pull rod 69, but is normally held in elevated position by the spring 77, so as to escape past the catch 73 40 without contact therewith, when the carriage is returning to its normal left hand marginal position.

Depression of the key 100, however, not only rocks the bell crank 103 and finger 109 to shift the universal clutch control bail 35 forwardly, and thus connect the clutch members 20, 21 to enable the motor 16 to drive the carriage 13 in letter spacing direction towards the beginning of a line, but also forces the thrust rod 114 downwardly to press its collar 117 against the eye 116 fixed to the catch reversing lever 118. Such pressure rocks the free end of the reversing lever 118 downwardly and the lever, in turn, rocks the extension 122 downwardly, which raises the catch 74.

As a result, the shoulder 123 of the partial return catch or extension 122 is brought into line with the catch 73 on the line space draw rod 69, and the catch 74 is displaced from its normal position.

Obviously, the displacement of the normal catch 74 is without significance, as, irrespective of its position, it would not function if the partial return catch 123 is in effective position, the partial return catch being arranged in front of the left hand margin catch 74, when the carriage is returning to the left.

Control by the operator of the interceptor carriage stopping means is conveniently effected as follows:

A strap 125 pivotally connected at its upper end, as at 126, to the eye 116, for instance, depends below the line space catch reversing lever 118, and is connected at its lower end to the leftwardly extending end of an interceptor stop 127.

This interceptor stop is loosely pivoted at its right hand end, at 128 (Figs. 1 and 3), to frame or casing of the carriage and is arranged to engage an abutment 129 projecting upwardly from a horizontal plate 130 secured at its rear edge to the rear rail 11 to stop the carriage in partially returned position. The strap 125 normally suspends the free left hand end of the interceptor stop at such a level as to clear said abutment.

The length of the interceptor stop member is such as to engage the abutment 129 to arrest the carriage at a point in the return movement of the carriage before it reaches fully returned position as for paragraphing, for example.

In the form shown in the drawings, the carriage, upon a partial return, is arrested about one and one-half inches to the right of the extreme left hand margin obtainable in the machine.

Obviously, such distance can be varied by adjusting the left hand margin stop 40 to the right from its extreme left hand adjustment, and the provision of means (not shown) for adjusting the banking abutment or the interceptor stop will admit of other relative variations between the point where the first line of a paragraph commences, and the extreme left hand margin.

In order to actuate the carriage return bail 35 to disconnect the clutch members 20, 21 just before the carriage is stopped by the engagement of the interceptor stop 127 with the abutment 129, the machine is provided with a longitudinally movable rod 131. The left hand portion of this rod is suspended for longitudinal movement upon the interceptor stop 127 by means of a bracket 132 secured to the interceptor stop and having a rearwardly bent portion at the lower end thereof which engages in a slot 133 formed by a cut-out in the rod 131 and a strip 134 secured to said rod. The right hand end of the rod 131 is pivoted to an arm 135 secured to a substantially vertical rock shaft 136 (see Figs. 2 and 4). This rock shaft is mounted to turn in a bracket 137 secured to the frame of the carriage and an arm 138 is attached to the upper end of said shaft. To this arm is pivoted a thrust rod 139 passing through an opening in the down-turned portion of an angle plate 140 secured to the framework of the carriage and the rear end of said rod 139 is arranged to engage the carriage return bail 35 when the rod is moved rearwardly. The arm 135 is acted upon by a coiled spring 141 which normally maintains the rod 131 in its left hand position determined by the engagement of the arm 138 with a suitable stop on the framework of the carriage and the rod 139 in advanced position out of engagement with the carriage return bail.

Thus the rod 131 is mounted on the carriage and moves with the carriage during the return movement thereof. The left hand end of the rod 131 is arranged to engage an abutment 142 on the frame during the return movement of the carriage when said rod is in its lowered position. The left hand end of the rod is held in elevated position so that it does not engage the abutment 142 during the full return movement of the carriage. The interceptor stop 127 is then held in elevated position in the manner above described and the left hand end of the rod 131 is held elevated therewith. When the interceptor stop 127 is depressed by the depression of the key 100 the left hand end of the rod 131 is depressed into position to engage the stop 142. As the carriage approaches the end of its partial return move-

ment, the movement of the rod 131 with the carriage is stopped by the engagement of the rod with the abutment 142 and the rock shaft 136 is then turned in a clockwise direction (Fig. 4) and a rearward movement is imparted to the rod 139 thereby engaging the rear end of said rod with the carriage return bail 35 and swinging said bail to the rear to disengage the members of the carriage actuating clutch.

When the key 100 is depressed to throw the partial carriage return mechanism into operation, the lever 118 is held in depressed position by a latch. This latch is released during the early part of the next advance movement of the carriage. In the construction shown, the lever 118 is held in depressed position by means of a latch 143 connected by a stud 144 (see Fig. 5) to said lever by a connection which permits relative pivotal movement between the latch and the lever about the axis of the stud and also permits the latch to swing with relation to the lever in a plane transverse to the lever. The latch is formed with a shoulder 145 arranged to engage beneath the horizontal portion 146 of the bracket 121 referred to hereinafter as a plate and said latch is acted upon by a coiled spring 147 which maintains the latch normally in engagement with the left hand edge (Fig. 3) of the plate. The upper portion of the latch engages in a slot 148 in an angle plate 149 secured to the framework of the machine which forms a guide for the latch.

During the normal operation of the machine the lever 118 is held in elevated position and the latch 143 occupies the position shown in Fig. 1. When the lever 118 is depressed by the depression of the key 100, the latch 143 is swung to the right to locate the shoulder thereon beneath the under side of the plate 146. Upon the release of the key the latch holds the lever 118 and all of the parts controlled from the lever in position during the partial return movement of the carriage.

The means for releasing the latch during the early part of the next advance movement of the carriage comprises a lever 150 (see Fig. 6) pivoted at 152 upon the plate 146 and arranged to engage the edge of the latch when swung in a counterclockwise direction from the position shown in said figure. The lever 150 is held in position out of engagement with the latch by means of a coiled spring 153 and its movement under the action of said spring is limited by means of a stop screw 154 threaded into the plate 146.

The lever 150 is swung in a counter-clockwise direction (Fig. 6) during the early part of the advance movement of the carriage by means of a lever 155 pivoted at 156 upon a block attached to a projection or arm 157 on the line space frame, the forward end of which lever is arranged to engage the upturned rear end portion of lever 150. The lever 155 is provided with a beveled face 158 which is engaged by the lever 150 during the return movement of the carriage. The movement of the lever 155 about its pivot 156 in a counter-clockwise direction (Fig. 6) is limited by means of a bracket 159 secured to the block on the arm 157 and the lever is acted upon by a coiled spring 160 which normally maintains the lever in engagement with the bracket 159.

With this construction, during the return movement of the carriage, the lever 150 engages the beveled surface 158 of the lever 155 and swings the latter lever in a clockwise direction (Fig. 6) until the lever 150 passes by the same. During the early part of the next advance move-

ment of the carriage the rear end of the lever 150 engages the forward end of the lever 155 which is then held in engagement with the bracket 159 thereby preventing any pivotal movement thereof in a counter-clockwise direction. The lever 155, therefore, swings the lever 150 in a counter-clockwise direction (Fig. 6) thereby actuating the latch to disengage the shoulder thereon from beneath the plate 146. This releases the lever 118 so that said lever can rise to its normal position thereby restoring to normal position all of the parts controlled by said lever.

Figures 7 and 9 of the drawings show a modified construction for effecting the disconnection of the members 20 and 21 of the carriage return clutch when the carriage reaches the end of its return movement. In this mechanism the carriage return bail 35 is swung rearwardly to effect the disconnection of the members of the clutch at the completion of the return movement of the carriage by means operated by certain parts of the line space mechanism. As shown in this figure, a thrust bar 161 is pivoted at 162 to the upper arm of the lever 66. This thrust bar passes through a guide in a bracket 163 secured to the bracket 43 by means of the stop 79. The left hand end of the thrust bar 161 is provided with a beveled face 164 arranged to engage the right hand end of the carriage return bail 35 when the thrust bar is moved to the left from the position shown in Fig. 7.

As the carriage completes its return movement the draw-rod 69 is moved to the left (Fig. 7) by the engagement of a contact on the carriage with the catch 73. This movement of the draw-rod swings the upper arm of the lever 66 in a counter-clockwise direction (Fig. 7) and moves the thrust bar 161 to the left through the guide 163. During this movement the beveled surface 164 of the left end of the thrust bar is engaged by the right hand end of the carriage return bail 35 and said bail is swung rearwardly to disengage the members of the clutch. As the draw-rod 69 is moved back to the right during the early part of the next advance movement of the carriage the thrust bar 161 is moved to the right therewith, thereby restoring the same to its normal position.

The machine is preferably provided with an escapement or letter feed mechanism of the type disclosed in the patent to Foothrap, No. 1,203,519, dated October 31, 1916, and controlled from the several letter and numeral keys of the type mechanism and from the space bar 165. The machine is also provided with an escapement release key 166 and connections between the same and the escapement mechanism as shown and described in said patent.

With this construction, when the writing is completed for a line before the carriage reaches the limit of its right hand movement and the operator desires to return the carriage to its fully returned position, he depresses the release key 166 allowing the carriage immediately to move to the right to the limit of its movement and thereby to throw in the carriage return mechanism or he repeatedly depresses the space bar 165 to secure the same result. When he desires the carriage return mechanism to return the carriage to partially returned position, he depresses the partial return key 100. Thus the carriage may be selectively returned to fully returned or partially returned position at the will of the operator.

Having explained the nature and object of

the invention and having specifically described a construction embodying the invention in its preferred form, what is claimed is:

1. A record making machine having in combination a type carriage movable in opposite directions transversely of the machine, type mechanism carried by said carriage, means for moving the carriage in a right hand direction during the operation of the type mechanism, power means for returning the carriage in a left hand direction, alternatively operative devices for stopping the carriage in its return movement in either of two different positions, means constructed for selective operation and each arranged to cause 15 the power means to be thrown into operation to return the carriage and mechanism controlled by one of said means for rendering operative one of said stopping devices.

2. A record making machine having in combination a paper support fixed in directions transverse to the machine, type mechanism, a type carriage for said mechanism movable in a right hand direction to letter space and in a left hand direction to return the type mechanism, means 25 for moving the carriage in a right hand direction during the operation of the type mechanism, power driven means for returning the carriage in a left hand direction, alternatively operative devices for stopping the carriage during its return movement in either of two different positions and common means for causing the power driven means to be thrown into operation and for rendering operative one of said stopping devices.

3. A record making machine having in combination a paper support, a key carriage movable with relation to the paper support in a right hand direction to letter space and in a left hand direction to return the same, type mechanism carried by said carriage, means for moving the carriage in a right hand direction during the operation of the type mechanism, power driven means for returning the carriage in a left hand direction, alternatively operative devices for stopping the carriage during its return movement in either of two different positions, key controlled mechanisms for throwing the power means into operation to return the carriage and means controlled by one of said mechanisms for causing one of said stopping devices to stop the carriage in a predetermined one of said positions.

4. A record making machine having in combination a key carriage movable in opposite directions across the machine, type mechanism carried by said carriage, means for moving the carriage in a right hand direction during the operation of the type mechanism, power mechanism for returning the carriage in a left hand direction, devices arranged to be rendered operative alternatively for stopping the return movement 55 of the carriage with the carriage in different positions, means controlled by the carriage for throwing the power mechanism into operation to impart a return movement to the carriage which is normally stopped by one of said stopping devices, and key controlled means for throwing the power mechanism into operation to impart a return movement to the carriage and for rendering another of said stopping devices operative to stop the carriage.

5. A recording machine having in combination type mechanism, a carriage movable in opposite directions across the machine, means for moving the carriage in one direction during a typing operation, power driven mechanism for impart-

ing return movements to the carriage, line space mechanism, operating means for said line space mechanism, two contacts spaced in the direction of movement of the carriage and selectively engageable with said operating means and means for selectively rendering said contacts alternatively operative to operate the line space mechanism at different points in the return movement of the carriage.

6. A recording machine having in combination type mechanism, a carriage movable in opposite directions transversely of the machine, means for moving the carriage in one direction to letter space, mechanism operated by power for returning the carriage in the opposite direction, line space mechanism, two contacts spaced in the direction of movement of the carriage through which the line space mechanism is operated, stops correspondingly spaced in the direction of movement of the carriage for stopping the carriage in different positions during its return and means for selectively rendering said contacts and said stops alternatively operative to operate the line space mechanism at different points in the return movement of the carriage and to stop the carriage in correspondingly different positions.

7. A recording machine having in combination type mechanism, a carriage movable in opposite directions transversely of the machine, means for moving the carriage in one direction to letter space, power mechanism for imparting return movements in the opposite direction to the carriage, line space mechanism, operating means for the line space mechanism, two contacts spaced in the direction of movement of the carriage and arranged to engage selectively with said operating means, power disconnecting means, connections for actuating the power disconnecting means from the line space mechanism and means for selectively rendering said contacts alternatively operative to operate the line space mechanism and the power disconnecting means at different points in the return movement of the carriage.

8. A recording machine having in combination type mechanism, a carriage movable in opposite directions across the machine, means for moving the carriage in one direction during a typing operation, power driven mechanism for imparting return movements to the carriage, line space mechanism, operating means for the line space mechanism, two contacts on the carriage spaced in the direction of movement thereof and selectively engageable with said operating means, and means for selectively rendering said contacts alternatively operative to operate the line space mechanism at different points in the return movement of the carriage.

9. A recording machine having in combination type mechanism, a carriage movable in opposite directions across the machine, means for moving the carriage in one direction during a typing operation, power operated mechanism for imparting return movements to the carriage, two stops on the carriage for stopping the carriage alternatively in different positions, line space mechanism and means for operating the line space mechanism from the movement of the carriage at the completion of the carriage movement to either position.

10. A record making machine having in combination a type carriage movable in opposite directions across the machine, means for moving the type carriage in one direction during a typ-

ing operation, means operated by power for imparting return movements to the carriage across the machine, mechanism for stopping the carriage in partially returned position, a key on the carriage and connections operative from the key in any position of the carriage for throwing in the power operated means and for rendering operative said mechanism for stopping the carriage.

10 11. A recording machine having in combination a frame, a carriage shiftable thereon in letter spacing direction and return, power actuated mechanism to return the carriage in contra-letter spacing direction to either fully or partially returned position, a key, mechanism controlled by the key for causing the return of the carriage, line space mechanism, means for arresting the return of the carriage with the carriage in the latter position and for operating the line space mechanism comprising a contact moved by the key from normal inactive position into position to actuate the line space mechanism during the return of the carriage, mechanism for holding the contact in operating position upon the release of the key until after the return movement of the carriage is completely arrested, mechanism for releasing thereafter the holding mechanism and means for restoring said contact to normal position upon its release.

15 12. A recording machine having in combination a frame, a carriage shiftable thereon in letter spacing direction and return, power actuated mechanism to return the carriage in contra-letter spacing direction to either fully or partially returned positions, a key, mechanism controlled by the key for causing the return of the carriage, a stop device controlled by the key for stopping the carriage in partially returned position, mechanism for holding the stop device in position upon the release of the key until the return movement of the carriage has been fully stopped by said device and means rendered operative by the movement of the carriage for actuating said holding mechanism to release said stop device.

20 13. A record making machine having in combination a carriage movable in opposite directions transversely of the machine, means for moving the carriage in letter spacing direction, mechanism operated by power for imparting return movements to the carriage, means for stopping the carriage in either of two different positions during its return movement, means for operating the line space mechanism before stopping the carriage in either of said positions and mechanism operated by the line space mechanism for throwing off the power before stopping the carriage.

25 14. A record making machine having in combination a carriage movable in letter spacing direction and return, means for moving the carriage in letter spacing direction during a typing operation, power actuated mechanism for imparting return movements to the carriage, a line space mechanism, means for stopping the return movement of the carriage with the carriage in either of two different positions, means for operating the line space mechanism just before the carriage reaches either of said positions, a carriage return bail for controlling the connection of said power mechanism with the carriage and means operated by the line space mechanism for operating the carriage return bail to throw off the power.

30 15. A record making machine having in com-

bination a carriage movable in letter spacing direction and return, means for moving the carriage in letter spacing direction during the typing operation, power operated mechanism for imparting return movements to the carriage, means for stopping the return movement of the carriage in either of two different return positions, line space mechanism, and means for operating the line space mechanism upon stopping the carriage in either of said positions comprising a longitudinally movable bar, selectively operable means for moving the bar longitudinally from the carriage during the latter part of the return movement of the carriage to either of said positions and mechanism for actuating the line space mechanism from the said longitudinal movements of the bar.

16. A record making machine having in combination a carriage movable in letter spacing direction and return, means for moving the carriage in letter spacing direction during the typing operation, power operated mechanism for imparting return movements to the carriage, a longitudinally movable rod, a contact carried thereby, a contact on the carriage for engaging the first contact adjacent the end of the carriage return movement, line space mechanism and means operated by the movement of said rod to disconnect the power mechanism from the carriage and for actuating the line space mechanism.

17. A record making machine having in combination a carriage movable in letter spacing direction and return, means for moving the carriage in letter spacing direction during the typing operation, power operated mechanism for imparting return movements to the carriage, a draft rod extending in the direction of movement of the carriage and moved longitudinally by the carriage as the carriage approaches the end of its return movement, line space mechanism operated by said rod means for stopping the return movement, a longitudinally movable thrust bar having a cam on one end thereof, connections for operating the thrust bar from said rod and means operated by said cam during the longitudinal movement of said thrust bar to disconnect the power mechanism from the carriage.

18. A record making machine having in combination a carriage movable in opposite directions across the machine, means for moving the carriage in one direction during a typing operation, mechanism operated by power for imparting return movements to the carriage, a carriage return bail for controlling the connection of the power mechanism with the carriage fixed in the direction of movement of the carriage, means controlled by said bail for throwing the power mechanism into and out of operation, manipulative means on the carriage for actuating the bail to throw the power mechanism into operation, a longitudinally movable thrust bar having a cam on one end thereof for engagement with the carriage return bail to actuate said bail to disconnect the power mechanism from the carriage and means for operating the bar from the movement of the carriage during the latter part of the return movement of the carriage.

19. A record making machine having in combination a carriage movable in letter spacing direction and return, means for moving the carriage in letter spacing direction in typing, power means for imparting return movements to the carriage, a line space mechanism and connections for operating the same from the movement of the carriage during the latter part of the

return movement of the carriage and means operated by the line space mechanism for disconnecting the power means from the carriage.

20. In a writing machine, the combination with 5 a frame of a carriage shiftable thereon in letter spacing direction and return, power means, normally disengaged connections between the power means and the carriage to return the carriage in contra letter spacing direction, means operable 10 to engage said connections, selectively controlled means on the carriage to limit variously, at will, the extent of contra letter spacing travel of the carriage, movable means, mechanism for shifting said means to a uniform extent during each return of the carriage irrespective of the extent 15 of the return movement and power disengaging means and line space mechanism both arranged to be operated by the shift of said means during each return of the carriage.

21. A record making machine having, in combination, a type carriage movable in opposite directions transversely of the machine, means for imparting letter space movements in a right hand direction to the carriage, power driven mechanism fixed in the direction of movement 25 of the carriage and having normally disengaged driving connections for returning the carriage in a left hand direction, alternatively operative devices for stopping the carriage in its return movement in either of two different positions, manipulative members carried by the carriage and arranged for selective operation, mechanism controlled by said members for engaging said driving connections to cause the return of the 30 carriage and means actuated by one of said members for rendering one of said stopping devices operative to stop the carriage in one of said positions.

22. A record making machine having, in combination, a substantially flat platen, a line space frame movable forwardly and rearwardly over the platen, a type carriage movable laterally on the line space frame, means for letter spacing the carriage during a typing operation, normally 40 inactive power driven mechanism for imparting return movements to the carriage mounted in fixed position on the line space frame, devices for stopping the carriage in either of two different return positions and manipulative means on the carriage for throwing said power driven mechanism into operation and for controlling one of the stopping devices to stop the carriage in a partial return position.

23. A record making machine having, in combination, a substantially flat platen, a line space frame movable forwardly and rearwardly over the platen, a type carriage movable laterally on the line space frame, means for moving the carriage to letter space, power driven mechanism for imparting return movements to the carriage fixed in the direction of movement of the carriage, manipulative means on the carriage and connections operated by said means for throwing in the power driven mechanism at any point in the letter spacing movement of the carriage, means on the carriage for causing the power driven mechanism to be thrown into operation at a predetermined point in the letter spacing movement of the carriage and automatic means for throwing out the power driven mechanism and stopping the carriage in either of two different return positions.

24. A record making machine having, in combination, a substantially flat platen, a line space frame movable forwardly and rearwardly over

the platen, a type carriage movable laterally on the line space frame, power driven mechanism mounted on the line space frame and fixed in the direction of movement of the carriage for imparting return movements to the carriage, means on the carriage and connections operated by said means for throwing in the power driven mechanism at any point in the letter spacing movement of the carriage, other means on the carriage and connections operated by said means for throwing in the power driven mechanism at a predetermined point in the letter spacing movement of the carriage and automatic means for throwing out the power driven mechanism at either of two different points in the return movement of the carriage and stopping the carriage in either of two different return positions.

25. A record making machine having, in combination, a frame, a carriage shiftable thereon in letter spacing direction and return, power operated mechanism for returning the carriage in contra-letter spacing direction, a stopping device for stopping the carriage in a predetermined returned position, manipulative means for positioning said device to stop the carriage, mechanism for holding the stopping device in position until after the movement of the carriage is arrested, means rendered operative by the movement of the carriage for actuating the holding mechanism to release said device and mechanism for restoring said stopping device to normal position.

26. A record making machine having, in combination, a frame, a carriage shiftable thereon in letter spacing direction and return, power operated mechanism for returning the carriage

in contra-letter spacing direction, line space mechanism, means for arresting positively the return movement of the carriage with the carriage in a predetermined position and operating the line space mechanism comprising a contact, means for moving said contact from its normal inactive position into operating position to actuate the line space mechanism during the return of the carriage, mechanism for holding the contact in operating position until the return movement of the carriage is completely arrested, means for thereafter actuating said holding mechanism to release the contact and means for returning the contact to its normal position.

15 27. A record making machine having, in combination, a carriage movable in opposite directions transversely of the machine, mechanism for moving the carriage in letter spacing direction, power means for returning the carriage in the opposite direction, line space mechanism, means for arresting the return movement of the carriage and operating the line space mechanism comprising a contact normally located in inactive position, manually controlled mechanism for throwing in said power means and for moving said contact into operating position to actuate the line space mechanism during the return movement of the carriage, mechanism for throwing out said power means during the return of the carriage, a retaining device for holding said contact in operating position until the movement of the carriage is arrested and means operated thereafter by the advance movement of the carriage for releasing said retaining device.

WILLIAM H. von HACHT.

CERTIFICATE OF CORRECTION.

Patent No. 2,283,400.

May 19, 1942.

WILLIAM H. von HACHT.

It is hereby certified that error appears in the printed specification of the above numbered patent requiring correction as follows: Page 8, first column, line 30, claim 16, after "mechanism" insert --to line space--; and that the said Letters Patent should be read with this correction therein that the same may conform to the record of the case in the Patent Office.

Signed and sealed this 28th day of July, A. D. 1942.

Henry Van Arsdale,

(Seal)

Acting Commissioner of Patents.
